* cited by examiner

Primary Examiner — Ian Simmons*Assistant Examiner* — Samantha Q Lawrence(74) *Attorney, Agent, or Firm* — Larson & Larson, P.A.; Frank Liebenow; Patrick Reid(57) **CLAIM**

The ornamental design for a blunt dissector, as shown and described.

DESCRIPTION

FIG. 1 is a front elevation view of a blunt dissector showing my new design;

FIG. 2 is a rear side elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a perspective view thereof.

The blunt dissector is shown with a break in its length, with the understanding that the portions of the article not shown in the drawings form no part of the claim design.
